UNITED STATES PATENT OFFICE.

PAUL R. HOSTETTER, OF YORK, PENNSYLVANIA.

TRAFFIC MARKER.

Application filed October 2, 1924. Serial No. 741,266.

To all whom it may concern:

Be it known that I, PAUL R. HOSTETTER, a citizen of the United States, residing at York, in the county of York and State of Pennsylvania, have invented new and useful Improvements in Traffic Markers, of which the following is a specification.

This invention relates to traffic pimplies and has for one of its objects to construct 10 a marker of reinforced concrete or the like capable of withstanding the wear and tear incident to the passage of traffic.

Another object of the invention is the provision of a traffic marker formed from a 15 material having inherent characteristics that render it visibly conspicuous in contrast to the color of the roadway.

Other objects of the invention will be disclosed as the description of the preferred 20 embodiment thereof proceeds.

In the drawings:

Figure 1 is a vertical section of my improved traffic pimple taken in a diametrical plane.

25 Figure 2 is a plan view of the reinforcement.

Referring now in detail to the several figures, the traffic marker consists of a skeletal reinforcement, represented in general by the reference character 1, a body of concrete or the like 2, molded in and about said reinforcement, and an anchor pin 3 having the inner end thereof embedded in the concrete and interlocked therewith.

35 The skeletal reinforcement comprises an annular curb-nosing 4 of metal having an inwardly directly web 5. The web is preferably formed with an undulating inner periphery 6, the peaks of which extend deep

40 into the concrete in a lateral direction, the alternating valleys between said peaks permitting undivided portions of concrete to extend outwardly beyond said peaks. The web is also preferably apertured behind said

45 peaks as shown at 7 in Figure 2 so as to leave the concrete unitarily bonded on both sides of said web. The masses of concrete in said valleys and the bonds of concrete in said apertures are so interleaved in the 50 plane of the web that a circle might be drawn intersecting both said masses and said bonds. This insures that there shall be no definite plane of cleavage between the web and the concrete along which the marker might disintegrate should it be subjected at any time to undue strain.

The marker in its preferred form preferably has the shape of an ellipsoid. That is to say, the bottom is flat while the top is convex, preferably conforming to a curvature produced by the revolution of a conic section around its axis. Metallic reinforcement is provided for bridging the space within the annular nosing this reinforcement taking the form of a cage having a flat bottom represented by the rods or wires 8 and a convex top formed by the rods or wires 9. These rods or wires are anchored to the nosing in any suitable manner, their arrangement being purely arbitrary and not vital to the invention in its broad aspect. In the preferred form I have shown the wires 9 lying in vertical planes some of which are perpendicular to others, while the rods or wires 8 lie in a horizontal plane, their arrangement being left in the main, to choice, it being highly desirable, however, that certain of these wires, for instance those designated as 8^a in Figure 2, should cross at approximately 80 the center of the marker so that they can be straddled by the cleft between the bifurcated portions 10 and 11 of the anchor pin 12. It is however, better that only a few but not all of the horizontal rods or wires should cross at the center, otherwise there would be a preponderance of metal with a corresponding dearth of concrete adjacent the central portion of the marker, resulting in structural weakness at that point.

Although I have, in the illustrative example of my invention used rods or wires as a reinforcement for bridging the space within the nosing, yet it is to be understood that other forms of metallic reinforcement might be substituted for the same without departing from the broad concept of the invention. For instance, expanded metal or other well known structural forms of reinforcement might be used with equal advantage.

The lower end of the anchor pin 12 is preferably cylindrical although it may be made in any shape desired and its function is to seat within a hole or socket in the roadway, holding the marker in position. It is preferred that the pin be rotatable in its socket so that the marker may bodily yield to the blows of traffic.

The skeletal reinforcement together with the anchor pin are properly positioned within an appropriate mold the latter being then

filled with concrete, and the metallic parts being so disposed that the nosing in the finished article remains exposed but flush with the concrete surfaces and that the reinforcing cage is embedded to an appropriate depth both at the top and bottom, the anchor pin being at the same time embedded in the concrete at a point where the marker is thickest, the bifurcated portions 10 and 11 of said pin forming a positive mechanical interlock with the concrete.

It becomes necessary in the case of the ordinary metallic markers now in use to repaint them at frequent intervals to restore them to a color which is visibly conspicuous against the color of the roadway. The present invention contemplates the obviation of repainting the markers by forming them at first hand with concrete mix of any suitable substance which dries white, or of such color that the marker is readily seen, and when once installed requires no further attention.

It will be understood that the convex shape of the rods or wires 9 causes them to form arches with the concrete in which they are embedded, the same intersecting one another at frequent intervals throughout the substance of the marker. This produces the strongest possible stress resisting surface for the marker which the wheels of heavy traffic will not disintegrate. The flat bottom portion of the cage reinforcement ensures the marker against breaking should it be placed upon uneven ground and also assists in the distribution of strains and in the prevention of local disintegration of the concrete, under impactive stresses.

While I have above described what I consider to be a preferred, and very practical form of the invention, it is to be understood that numerous changes and alterations may be made in the form and arrangement of the parts, and particularly in the distribution of the reinforcing wires, without departing in any way from the spirit of the invention.

Having described my invention what I claim as new and desire to secure by Letters Patent, is:—

1. A traffic marker formed of refractory substance having the top and base faces asy whole, and a metallic reinforcement embedded therein comprising an annular nosing, and reinforcing elements secured to said nosing and bridging the space thereacross, said elements being spaced apart in the direction of thickness of said marker some of said elements being arranged to conform substantially to the shape of the base and some being arranged to conform substantially to the shape of the top.

2. A traffic marker formed of refractory substance having a convex top and a flat base, and a metallic reinforcement embedded

therein comprising an annular nosing and reinforcing means secured to said nosing and bridging the space thereacross, said means being spaced apart in the direction of thickness of said marker a part of said means being arranged to conform to the shape of the base and a part being arranged to conform to the shape of the top. 70

3. A traffic marker formed of refractory substance having a convex top and a flat base, and a metallic reinforcement embedded therein comprising an annular nosing, rods secured to said nosing and bridging the space thereacross, said rods being spaced apart in the direction of thickness of said marker some of said rods being arched to conform to the shape of said top and some being stretched chordally in a plane substantially parallel to the plane of the base. 75

4. A traffic marker formed of refractory substance having a convex top and a flat base, and a metallic reinforcement embedded therein comprising an annular nosing, rods secured to said nosing and bridging the space thereacross, said rods being spaced apart in the direction of thickness of said marker some of said rods being arched in vertical intersecting planes to conform substantially to the shape of the top and some being stretched chordally in a plane parallel with the base. 80

5. A traffic marker formed of refractory substance having a convex top and a flat base, an anchor pin projecting from said base having the inner end thereof embedded in said refractory substance and provided with an opening, metallic reinforcement embedded in said refractory substance comprising an annular nosing and rods secured to said nosing and bridging the space thereacross, some of said rods being arched to conform substantially to the shape of said top and some being stretched chordally in a plane substantially parallel to the base, a group of the latter rods intersecting substantially axially of said anchor pin and passing through the opening thereof. 95

6. A traffic marker formed of refractory substance and a metallic reinforcement embedded therein comprising an annular nosing formed with an inwardly extending web provided with a series of apertures, and reinforcing elements secured to said web and bridging the space across said nosing. 105

7. A traffic marker formed of refractory substance and a metallic reinforcement embedded therein comprising an annular nosing provided with an inwardly extending web, said web being formed with an undulating inner periphery and reinforcing elements secured to said web and bridging the space across said annular nosing. 110

8. A traffic marker formed of refractory substance and a metallic reinforcement embedded therein comprising an annular nos- 125

- ing provided with an inwardly extending web, said web being formed with an undulating inner periphery and with a series of apertures extending into the peaks of said periphery, and reinforcing elements secured to said web and bridging the space across said annular nosing. 5
9. A traffic marker formed of refractory substance having a convex top and flat base, 10 a metallic reinforcement embedded therein comprising an annular nosing having an inwardly extending intermediate web, said web
- being formed with an undulating inner periphery and with a series of apertures extending into the peaks of said periphery, 15 rods secured to said web and bridging the space across said annular nosing, some of said rods being arched in vertical intersecting planes to conform substantially to the shape of the top and some being stretched 20 chordally in a plane parallel with the base.

In testimony whereof I have hereunto set my hand.

PAUL R. HOSTETTER.
